5 Claims.

(CL 178—44)

This invention relates to thermionic valve circuits for controlling or producing electric pulses as used, for example, in television systems.

It is known to employ the properties of delay networks in circuits for generating electric signal pulses or effecting selection of pulses of predetermined duration from a mixture of pulses. In particular, in the specification of co-pending United States Patent application Serial No. 193,401, now Patent No. 2,211,942, issued August 20, 1940, it is proposed to use a delay network in an arrangement for separating frame synchronising pulses from line synchronising pulses. The line and frame pulses are applied to two channels simultaneously and in one channel they are delayed by an amount greater than the duration of a line pulse but less than that of a frame pulse. The delayed and undelayed pulses are then applied to a hexode valve, a double diode or a double triode circuit, so that an output is obtained only when the pulses overlap in time, that is to say, at the occurrence of a frame pulse.

Again, in the specification of co-pending United States Patent application Serial No. 202,452, now Patent No. 2,212,967, issued August 27, 1940, a circuit arrangement is described including an impulse generator which is started and stopped by control impulses, the starting and stopping pulses originating from a single signal passing along a delay network. In one arrangement a valve of a multi-vibrator is started into operation when a pulse passing through a delay network connected across the valves of the multi-vibrator reaches a first tapping in the network and is stopped when the same pulse reaches a second tapping, a square topped wave of the duration determined by the delay between the tappings being generated.

Also in the specification of co-pending United States Patent application Serial No. 202,452 it is proposed to produce a pulse of a shorter width than a controlling pulse by switching on a hexode valve by the controlling pulse applied to its inner grid and switching the valve off by a negative pulse delayed by a network the required time with respect to the first pulse, the delayed pulse being applied to the outer grid of the hexode.

Further, in the specification of co-pending United States Patent application Serial No. 269,397, it is proposed to employ two valves having a common cathode impedance, the pulses to be mixed or from which selected pulses are to be derived, being applied to the control grids. An output can be taken from either anode or from

both in push-pull. By applying a saw-tooth waveform with a sharp leading edge to a delay network across which the two grids are connected, a pulse is formed in the anode circuit having a duration equal to the distance between the tappings on the delay network.

In the preceding arrangements the delay networks are operated with correct terminations so that reflectionless working is obtained. It has been found, however, that in certain cases economy of the length of the delay network required and in most cases in the number of valves required, can be effected by a mis-terminating the delay network so that use is made of the reflected wave, the present invention having as its basis the use of the reflected wave for switching purposes. The object of the present invention is to provide alternative forms of circuit arrangement for generating pulses of a required duration and/or for separating mixed pulses and which effect the economies referred to.

According to the present invention a circuit arrangement includes a delay network connected to a source of pulses and a switching device, said delay network having a termination such that an input pulse is reflected from the end of the network, said switching device being controlled by the combined operation of the input pulse and the reflected pulse.

Certain circuit arrangements according to the present invention for generating pulses of a required duration and/or separating pulses of one duration from pulses of another duration include a delay network and means for feeding pulses to the delay network which is provided with a tapping or tappings from which the required pulses are derived, the said delay network being mis-terminated at the end remote from that to which the pulses are fed, so that a pulse, which may be derived from an input pulse which it is desired to separate from pulses of shorter duration, is developed by the combined operation of the original pulse travelling down the delay network and the pulse reflected from the remote end.

One feature of the invention consists in terminating the delay network at one end by an impedance substantially equal to the characteristic impedance of the network and said impedance may be constituted by the source of pulses or by the load. A further feature of the invention consists in arranging that at the end remote from the source of input pulses, the delay network is either short-circuited or open circuited for frequencies in the operating range.

In order that the invention may be more

clearly understood and readily carried into effect, alternative forms of pulse operated circuits embodying the invention will now be described by way of example with reference to Figures 1 to 4 of the accompanying drawings.

Referring to Figure 1 of those drawings, an arrangement is shown for generating a pulse of predetermined duration from an input pulse of longer duration. The arrangement shown might be used, for example, to develop a line synchronising pulse from a line frequency saw-tooth waveform having a very steep leading edge, or from a pulse of longer duration such as the suppression pulse which normally commences slightly ahead of the synchronizing pulse and terminates slightly after. In Figure 1, a cathode follower valve 1 having its cathode resistance 2 connected to a negative point in a source of voltage supply feeds through a resistance 3 a delay network 4. The resistance 3, together with the internal impedance of the valve 1 and resistance 2, constitutes a generator, the impedance of which is substantially equal to the characteristic impedance of the delay network 4. Any other suitable form of generator may be used providing its impedance substantially matches the surge impedance of the delay network. The tapping point 5 in the delay network 4 is coupled through a condenser 6 to the control grid of an output valve 7 serving as a limiting device. The pulse required to be generated can be taken from the anode circuit of the valve 7 at the terminal 8.

In the arrangement shown the valve 1 is arranged to produce a negative pulse at the terminal 8 on the application of a positive pulse from the valve 1. The condenser 6 and the resistance 9 connected between the control grid and cathode of the valve 7 ensures that this valve is self-biasing, the time constant of the condenser/resistance combination being long compared with the duration between pulses and the peaks of the pulses applied to the control grid causing grid current to flow. It will, of course, be understood that any convenient biasing means may be employed.

An arrangement alternative to that shown in Figure 1 may consist of a pair of valves arranged to operate in push-pull and replacing the valve 1, such an arrangement being described in the specification of United States Patent No. 2,185,367, and in this case the control grid of the second valve would be effectively earthed for alternating currents. A pair of valves so connected would form an automatic limiting arrangement for pulse amplitude.

The operation of the circuit described with reference to Figure 1 is as follows: The saw-tooth waveform or pulse of long duration fed from the valve 1 enters the delay network in the positive sense and on arriving at the tapping point 5 renders the valve 7 conductive. The pulse travels down the delay network and arrives at the far end which is short-circuited by a link 10. The pulse is then reflected from this short-circuited end, the sense of its voltage being reversed and on again reaching the tapping point 5, it will cancel the effect of the original positive voltage applied at this point, switching off the valve 7 and thus terminating the pulse available at the output terminal 8. The reflected pulse will travel on and be dissipated in the internal impedance of the input generator which, as previously indicated, is matched to the surge impedance of the network 4.

The duration of the pulse available at the terminal 8, initiated at the point 5 by the input

pulse and terminated at the same point by the reflected pulse will be substantially equal to twice the period of the delay between the tapping point 5 and the remote end 10 of the network. The pulse taken from the tapping point 5 will lag the input pulse by the amount of delay network between the generator and the tapping point. If the tapping point were removed to the generator, no delay of course would be obtained.

If a saw-tooth waveform input is applied to the network and the long flank of the saw-tooth is uniform, the slow portion of the last reflected pulse will cancel the slow changing portion of the incoming pulse so that a substantially squared pulse will be taken from the point 5 subject to any slope due to the inevitable loss in the delay network.

The circuit arrangement of Figure 2 illustrates a method of generating two consecutive pulses from a single saw-tooth pulse input. In Figure 2, the input valve 1 is shown driving the delay network 4 from its anode, a feed resistance 11, coupling condenser 12 and terminating resistance 13 forming in combination a generator, the impedance of which matches the surge impedance of the delay network 4. The waveform used by the British Broadcasting Corporation for the television transmission system at present in use constitutes an example of a case in which it is desired to produce two pulses from a saw-tooth. The waveform referred to is described in an article entitled The Marconi-E. M. I. Television System in the Journal of the Institution of Electrical Engineers for December, 1938, and commencing at page 758. In the case of the waveform referred to, two frame synchronising pulses are generated from a single line frequency saw-tooth wave with a steep rising waveform.

Assuming the input signals to be applied with a quick change from negative to positive and a slow change from positive to negative in the delay network, the two valves 14 and 15 are so biased that the valve 14 is normally non-conductive and the valve 15 is conducting. The steep portion of the saw-tooth wave must be of sufficient amplitude after attenuation due to transmission in both directions along the delay network as to be about twice the discriminating bias applied to the valve 14. These valves operate in a similar manner to the pair of valves described in the specification of co-pending United States Patent application Serial No. 269,397 previously referred to. Thus the quick rise of the saw-tooth pulse arriving at valve 14 from the tapping point 16 renders this valve conductive and the valve 15 non-conductive. The quick rise on arriving at the tapping point 17 renders the valve 15 conducting and consequently the valve 14 non-conducting, so terminating the first generated pulse. The quick rise is then reflected from the short-circuiting link 18 in reverse sense as regards its voltage and on again arriving at the point 17 renders the valve 15 non-conducting and the valve 14 conducting. The reflected pulse then arrives at the point 16 rendering the valve 14 non-conducting and the valve 15 conducting and so terminating the second generated pulse. Finally, the reflected pulse arrives at the generator which as previously indicated constitutes a matched terminating impedance and is dissipated. The slow uniform falling portion of the saw-tooth pulse is cancelled as regards its effect on the valves 14 and 15 apart from any loss occurring in the network by the reflected wave cancelling the forward travelling wave. The output of the

double frequency pulse may be obtained from either of the anodes of the valves 14 and 15.

As an example of the timing of the pulses in the arrangement shown in Figure 2, it is convenient to consider the synchronising pulses of the waveform in the Marconi-E. M. I. television system previously referred to. These pulses are required to be each of approximately 40 micro-seconds duration separated by intervals of 10 micro-seconds. The delay between the tapping for the valve 15 and the short-circuited end of the delay network should therefore be 5 micro-seconds and the delay between the two tapping points 16 and 17 should be 40 micro-seconds. The amount of delay between the generator and the tapping point 16 is determined by the relative phase of the input pulses and the required beginning of the first frame pulse. Alternatively, instead of generating the pulses, the generation may in fact, consist of the intervals between the pulses and in this case the delay required between the tapping point 17 and the short-circuited end of the delay network would be 20 micro-seconds, the delay between the tappings 16 and 17 being 10 micro-seconds. The delay between the generator and the tapping point 16 would be that required between the start of the quick rising portion of the saw-tooth and the end of one of the frame pulses.

In the arrangements described with reference to Figures 1 and 2 it has been assumed that the quick travelling portion of the input pulse represents a positive rise, but the arrangements are equally applicable to a pulse changing rapidly from positive to negative. If such a pulse is required with the arrangement of Figure 2, it will be necessary to interchange the standing biasing potential applied to the control grids of the valves 14 and 15.

Referring again to Figure 1, if the short-circuiting link 10 at the end of the delay network is omitted, the network, thus being open circuited at the end remote from the generator, the arrangement may be used to effect separation of pulses of long duration from those of shorter duration. Thus, for example, assuming signals including vision signals, line synchronising pulses of 10 micro-seconds duration and frame synchronising pulses of 40 micro-seconds duration are applied to the input so that the synchronising pulses are present in delay network in the positive direction, and assuming further that the delay between the tapping point 5 and the remote end of the delay network is greater than 5 micro-seconds, for example, 10 micro-seconds, then the largest positive pulses arriving at the grid of the valve 7 will be those due to the frame synchronising pulses which appear first at the grid of the valve 7 as a forward travelling wave and are reflected from the open end of the delay network, re-appearing at that grid in addition as a reflected wave, thus giving a double synchronising amplitude at the grid due to the frame synchronising pulses. Line synchronising pulses will appear at the grid of valve 7 due to the forward wave, but the contribution due to the forward wave will have ceased by the time the contribution due to the reflected wave returns to the generator from the open end of the network. If the valve 7 is biased automatically or otherwise only to pass the pulse representative of the addition of a synchronising pulse occurring simultaneously in the forward and reflected waves, the valve 7 will serve to give an output which represents the frame synchronising pulses, thus

acting as a limiting device. In general, with such an arrangement no delay network would be included between the generator and the connection to the control grid of the valve 7.

Referring again to Figure 2, if the total delay of the network 4 is equal to half the frequency of the applied saw-tooth, the reflected saw-tooth exactly neutralises the voltage appearing across the input from the generator assuming no loss occurs in the delay network so that the generator delivers purely current and no voltage. In these circumstances it is not theoretically important to ensure that the surge impedance of the delay network and the internal impedance of the generator are matched, but in practice, an approximate match is desirable in order to allow for loss in the delay network and any error of matching of the exact delay and the voltage of the applied saw-tooth.

Figure 3 of the drawings shows a further application of the reflecting delay line to the production of an observation pulse. The television waveform already mentioned includes after every line synchronising pulse a period of at least 5 micro-seconds at an amplitude representing black. Similarly, following the frame frequency pulse there is a longer black period, so that there is always a minimum 5 micro-seconds following the end of any synchronising pulse. It may be required to observe the amplitude of the 5 micro-second, black period either for the purpose of automatic volume control or for example, as described in the specification of co-pending United States patent application Serial No. 69,831, now Patent No. 2,224,134, issued December 10, 1940, for the purpose of re-establishing the D. C. or fixing the black level as described, for example, in the specification of co-pending United States patent application Serial No. 40,532, now Patent No. 2,190,753, issued February 20, 1940. For any of these purposes a switching pulse is required, capable of operating observation or fixing devices during the 5 micro-seconds black period. Such a switching pulse desirably may begin slightly after the beginning of the 5 micro-seconds black period and end just before the end of the 5 micro-seconds black period, the switching pulse having a duration of say 4 micro-seconds. The circuit of Figure 3 shows a suitable means of obtaining this pulse.

The combined signal with synchronising pulses in the positive sense and picture signals negative, is led to a separating valve 19 which is self-biasing and operates as described in the specification of co-pending United States patent application Serial No. 720,205, now Patent No. 2,252,746, issued August 19, 1941. The separate synchronising signals appear in the anode circuit across the resistance 20 which matches the surge impedance of the delay network 4. This delay network is short circuited at the far end by the link 10. At the top, say $\frac{1}{2}$ micro-second after the beginning of the delay network, a lead is taken to the grid of a further valve 21. At the beginning of the synchronising pulse the potential at the anode of the valve 19 drops negatively and a negative wave is propagated along the delay network and reflected as a positive wave, which, arriving back at the anode, cancels the original negative voltage across the resistance 20. The valve 21 is so biased that it is unaffected by the negative pulse. At the end of the synchronising pulse however, when the anode current of the valve 19 is cut off, a posi-

tive wave travels down the delay network applying a positive voltage to the grid of valve 21. The wave travels down the delay network and is reflected as a negative wave by the termination 10, travelling backwards along the delay network, cancelling the positive voltage on the grid of the valve 21, and finally cancelling the positive voltage on the anode of the valve 19. If the delay from the anode of the valve 19 to the grid of the valve 21 is $\frac{1}{2}$ micro-second, the positive pulse of the grid of the valve 21 will start $\frac{1}{2}$ micro-second after the pulse on the anode of the valve 20. If the remainder of the delay is 2 micro-seconds, there will be a positive pulse of 4 micro-seconds duration on the grid of the valve 21 until the returning wave cancels the positive pulse. The valve 21 may be biased in the same manner as the valve 19, or in the alternative manner shown in the figure. The grid is connected through a leak resistance 22 to ground and the cathode is connected through a high resistance 23 to a source of negative potential. A condenser 24 shunts the resistance 23 to ground. The resistance is so proportioned that the current passed by the valve 21 during each effective pulse, charges the condenser positively and sufficient to maintain the cathode at such a potential as to pass a required current through the valve. As it is possible to obtain quite large signals on the grid of this valve, a further resistance 25 is inserted between the condenser and the cathode to reduce the slope of the valve, so that small irregularities on top of the wave do not produce large irregularities in the output signal of the valve 21. Alternatively, two valves as described in the specification of co-pending United States patent application Serial No. 269,397 may be employed to give a limiting action so that the amplitude of the output wave is unaffected by slight variations in amplitude of the wave arriving from the delay network.

Consideration of the circuit shown in Figure 3 will make it clear that the connections of the anode of the valve 19 and the control grid of the valve 21 may be interchanged. If such an interchange of connections is effected it will be seen that the delay network 4 is not fed from a source of signals having an impedance equal to its characteristic impedance but is in fact feeding into such an impedance.

Figure 4 shows a further application of the reflecting delay network to a television receiver. The basic principle is as described with reference to the modified form of Figure 1 shown in Figure 3. Television signals from, for example, an amplifier following the rectifier of a receiver are fed in at the terminal 26 with the picture signals in the positive sense and the synchronising signals negative. The D. C. is re-established by means of a diode valve 27 and leak resistance 28 as described in the specification of co-pending United States patent application Serial No. 720,205 previously referred to. The anode of the diode 27 is held at a suitable positive potential, which for example may be such that the bottom of the synchronising signals gives a potential on the cathode of the following valve 29 of about +20 volts. The valve 29 is of the cathode follower type having a potentiometer 30 in its cathode lead, from which the vision signals for the receiver cathode ray tube are taken by the lead 31. The potentiometer 30 may have a value, for example, of 5000 ohms and the incoming signals may be such that there are 5 volts of synchronising signal and 12 $\frac{1}{2}$ volts of picture signal on the cathode of the

valve 29. With these voltages, the currents through the valve would alter by 1 m. amp. for synchronising signals and 2 $\frac{1}{2}$ m. amps. for picture signals, apart from quick impulse changes due to the inevitable capacity to ground of the cathode of valve 29. Coupled to the cathode of this valve is the cathode of the line separating valve 32. The grid of this valve is maintained at a potential such that when its cathode is at say 60 volts, the valve will pass 2 m. amps. Between the cathodes of the valve 29 and the valve 32 are arranged a condenser 33 and resistance 34, whose function is to bias the cathode of the valve 32 automatically so that it passes 2 m. amps. during synchronising signals and is cut off for other amplitudes. In the example given, if the synchronising signals occupy about 10% of the picture period, the average current to the cathode of the valve 32 will be 0.2 m. amp., so that the resistance should, with the 40 volts difference of cathode potential, be some 200,000 ohms, which may be shunted by a condenser of $\frac{1}{2}$ microfarad or more. Synchronising signals appear on the anode of the valve 32, and a capacity connection, not shown, from the anode resistance 35 may pass these signals to the line synchronising generator.

Owing to the fact that during the synchronising signals the valve 32 absorbs some 2 m. amps., which would normally flow to the valve 29, the current change due to the synchronising signals is increased from 1 m. amp. to about 3 m. amps., thus allowing large synchronising signals comparable in amplitude to the picture signals to be obtained across the anode resistance 36 and delay network 4 in the anode lead of the valve 29. This open circuit delay network 4, has about 10 microseconds delay operated as described with reference to the modified form of Figure 1, to give an extra positive amplitude only for frame synchronising pulses which continue for long enough to allow the reflected wave to add to the undelayed wave. The signals so obtained are passed to the valve 37 which may be self-biasing as described in the specification of co-pending United States patent application Serial No. 720,205.

An alternative biasing arrangement is shown in Figure 4, the grid leak 38 of the valve 37 being taken to the same source of potential as the grid 50 of valve 29, so that when the valve 37 passes about 2 m. amps., its cathode will be positive in the order of 60 volts. The cathode is fed by the high resistance 39 from earth, designed to pass the necessary mean current which for 8 frame synchronising pulses occurring every 50th of a second each effectively 20 microseconds long, is about 16 micro-amperes requiring a cathode resistance of 3.5 megohms. The cathode condenser 40 which stores this positive bias is shown connected to the anode decoupling condenser 41 of the valve 29, so that any variations of H. T. voltage which are operative to change the grid potential, will also change the cathode potential. The decoupling condenser 41 may be of 2 micro-farads and the cathode condenser 40 of the valve 37 may be for example 1 microfarad. The high cathode resistance provides in effect a D. C. re-establishment differing from the type described in the specification of co-pending United States patent application Serial No. 720,205 previously referred to, in that the cathode current itself is used to build up the necessary bias. Separate frame synchronising impulses may be taken from the anode of the valve 37.

The delay networks shown may be of any known

form having the necessary number of sections to give the required sharpness of pulse. The coils of adjacent sections may be coupled together for example to give an improved uniformity of delay characteristic. The delay networks may have M-derived sections adjacent to the terminations. As the delay is not constant for all frequencies, and is in error for frequencies approaching the cut-off, it may be found advisable to shunt the first coil or first few coils with high resistances which tend to attenuate the high frequencies and thus while possibly reducing the sharpness of the wave-front prevent reflection irregularities arising.

While certain applications of the invention have been indicated, it will be understood that the invention may be widely applied.

Thus, in the case of a transmission system employing interlacing, difficulty is often experienced due to interaction between the line scanning circuits and the frame scanning circuits. The basis of such interaction is that one frame return stroke is half a line out of step relative to the line scanning as compared with the other frame return stroke and the effects of interaction between the line and frame circuits are not the same for two frame scans. The interaction is usually due to stray couplings which are affected by the relatively large voltages and currents occurring in the line scanning circuit during the rapid return stroke and as these currents are varying rapidly, inductive stray couplings are easily affected by them. The back coupled voltages operate either to trip the frame scanning circuit slightly earlier in one frame scan than the other, or they may delay the tripping of the frame scanning circuit. Such an effect corresponds to a slight delay or advance of the effective frame synchronising pulse in alternate frame scans. Even if there is no timing error as described in the frame scan, the stray couplings may produce a displacement error.

The generation of the saw-tooth controlling the frame scan is effected by what is essentially a non-linear device, for example, the discharging valve of the saw-tooth generator. If during the period of such a discharge a line scan voltage is induced in the discharging circuit, this voltage may alter the potential to which the condenser is discharged, thereby spoiling the interlace. In severe cases the displacement may amount to several line widths although the frame timing is perfect.

Assuming it can be arranged that the whole process of tripping the frame scanning circuit and developing the quick portion of the frame deflecting saw-tooth occurs for both the frames during a portion of the forward stroke of the line scan, the interlacing troubles mentioned would not be so serious because a first order inductive coupling is only affected by the relatively slow changes during the forward line stroke and the rate of change is approximately constant during the whole of the forward stroke.

The method of using the arrangement of Figure 1 for separating pulses described previously may be adopted in the present instance. Instead of the deflecting waveform generating valve being tripped on the occurrence of a frame pulse the effect of the frame pulse on the frame scanning circuit is delayed by, for example, 20 micro-seconds. Thus, in the case of the frame pulse coincident with a line pulse, the return stroke of the line will have ceased during this 20 micro-seconds. Similarly in the case of the

frame pulse not coincident with the line pulse there will be a delay of 30 micro-seconds before the beginning of the next line pulse. It is therefore necessary to provide a blocking oscillator or other relaxation device which will complete its quick stroke in less than 30 micro-seconds so that the charging of the saw-tooth condenser or other reactance is completed before the beginning of the next line return. This can be effected by the ordinary blocking oscillator valve by using an efficient valve of high slope and a blocking oscillator transformer of, for example, twice the number of turns normally employed for a line blocking oscillator. By using a valve with high slope sufficient charge can be accumulated in a sufficiently large condenser to allow this blocking oscillator to work at frame frequency with an active period considerably shorter than 30 micro-seconds. Broadly speaking, the circuit following this condenser is operating linearly so that it does not rectify small induced voltages from the line scanning circuit and the arrangement should permit perfect interlacing to be obtained despite small cross couplings.

Modifications in detail may, of course, be effected in carrying out the invention and, for example, while reference has been made to limiting devices constituted by thermionic valves having a control grid or electrode, it will be understood that other forms of limiting device may be employed, such for example as a diode valve. Again, while in the description of Figure 3 reference has been made to the use of a pair of valves having the cathodes connected to a common impedance, it will be understood that a double triode valve having a single cathode may be employed.

I claim:

1. An electrical impulse converting system comprising an electrical delay network having a predetermined characteristic impedance and both input and output terminals, a thermionic electrical impulse source connected to said input terminals to transmit electrical impulses to said network, said network being terminated at said input terminal by an impedance substantially the same magnitude as said characteristic impedance and being mismatched as to said characteristic impedance at said output terminals to provide reflected impulses from said transmitted impulses, a thermionic device, adjustable means to connect said thermionic device to said network to receive both the transmitted and the reflected impulses to vary the time interval between the receipt of the transmitted impulses and the receipt of the reflected impulses at said thermionic device and to vary the time interval between the transmission of impulses from said source to said network and the receipt of said transmitted impulses at said thermionic device, and means to derive output impulse energy from said thermionic device, said output impulse energy characteristic being controlled by the time difference between said transmitted and said reflected impulses.

2. An electrical impulse converting system comprising an electrical delay network having a predetermined characteristic impedance and both input and output terminals, a thermionic electrical impulse source connected to said input terminals to transmit electrical impulses to said network, said network being terminated at said input terminals by an impedance substantially the same magnitude as said characteristic impedance and being short-circuited at said out-

put terminals to provide reflected impulses of opposite polarity from that of said transmitted impulses, a thermionic device, adjustable means to connect said thermionic device to said network to receive both the transmitted and the reflected impulses to vary the time interval between the receipt of the transmitted impulses and the receipt of the reflected impulses at said thermionic device and to vary the time interval between the transmission of impulses from said source to said network and the receipt of said transmitted impulses at said thermionic device, and means to derive output impulse energy from said thermionic device, said output impulse energy characteristic being controlled by the time difference between said transmitted and said reflected impulses.

3. An electrical impulse converting system comprising an electrical delay network having a predetermined characteristic impedance and both input and output terminals, a thermionic electrical impulse source connected to said input terminals to transmit electrical impulses to said network, said network being terminated at said input terminals by an impedance substantially the same magnitude as said characteristic impedance and being open-circuited at said output terminals to provide reflected impulses of the same polarity as that of said transmitted impulses, a thermionic device, adjustable means to connect said thermionic device to said network to receive both the transmitted and the reflected impulses to vary the time interval between the receipt of the transmitted impulses and the receipt of the reflected impulses at said thermionic device and to vary the time interval between the transmission of impulses from said source to said network and the receipt of said transmitted impulses at said thermionic device, and means to derive output impulse energy from said thermionic device, said output impulse energy characteristic being controlled by the time difference between said transmitted and said reflected impulses.

4. An electrical impulse converting system comprising an electrical delay network having a predetermined characteristic impedance and both input and output terminals, a thermionic electrical impulse source connected to said input terminals to transmit electrical impulses to said network, said network being terminated at said input terminals by an impedance substantially

the same magnitude as said characteristic impedance and being mismatched as to said characteristic impedance at said output terminals to provide reflected impulses from said transmitted impulses, two electron discharge tubes each having a cathode, control electrode and an anode, adjustable means to connect each control electrode of said electron discharge tubes to said network to receive both the transmitted and the reflected impulses to vary the time interval between the receipt of the transmitted impulses and the receipt of the reflected impulses at said control electrodes and to vary the time interval between the transmission of impulses from said source to said network and the receipt of said transmitted impulses at said control electrodes, and means to derive output impulse energy from said anodes of said electron discharge device, said output impulse energy characteristic being controlled by the time difference between said transmitted and said reflected impulses.

5. An electrical impulse converting system comprising an electrical delay network having a predetermined characteristic impedance and both input and output terminals, a thermionic electrical impulse source connected to said input terminals to transmit electrical impulses to said network, said network being terminated at said input terminals by an impedance substantially the same magnitude as said characteristic impedance and being mismatched as to said characteristic impedance at said output terminals to provide reflected impulses from said transmitted impulses, a thermionic device, adjustable means to connect said thermionic device to said network to receive both the transmitted and the reflected impulses to vary the time interval between the receipt of the transmitted impulses and the receipt of the reflected impulses at said thermionic device and to vary the time interval between the transmission of impulses from said source to said network and the receipt of said transmitted impulses at said thermionic device, means to derive output impulse energy from said thermionic device, said output impulse energy characteristic being controlled by the time difference between said transmitted and said reflected impulses, and biasing means connected to said thermionic device to provide output impulse energy only when said transmitted and reflected impulses are superimposed with the same polarity.
